UNITED STATES PATENT OFFICE.

FRANK S. THOMAS, OF TOPEKA, KANSAS.

DESIGN FOR A DESK OR CABINET.

SPECIFICATION forming part of Design No. 35,395, dated December 3, 1901.

Application filed June 28, 1901. Serial No. 66,435. Term of patent 14 years.

To all whom it may concern:

Be it known that I, FRANK S. THOMAS, a citizen of the United States of America, residing at Topeka, in the county of Shawnee and State of Kansas, have invented and produced a new and useful Design for Desks or Cabinets; of which the following is a specification, reference being had to the accompanying drawing, which is a perspective view showing the design.

The base A is divided on its vertical center by a molding a into equal divisions, similar moldings being at the ends, such moldings having finishing-pieces between which at the bottom is the base-board a' and at the top horizontal pieces a^2 . The space between the end and the central molding is occupied by drawers A' , which are of the same length on each side, the number of spaces which receive the drawers being such that the width of the base A will greatly exceed its height.

Upon the top of the base A there is an upper case or cabinet, the depth thereof being less than the depth of the base, providing at the front and top of the base a ledge or shelf which is slightly inclined, such shelf being much greater than the ledges which project at the sides.

The width of the upper section B of the cabinet is the same as the width of the lower section A, and such upper section has at each end two vertical sets of pigeonholes d , the lower pigeonholes being smaller vertically than those above, and centrally there is a vertical partition D. To the right of the partition D and adjacent to the right-hand set of pigeonholes is a partition D', to the right of such partition there being a narrow vertical compartment. The pigeonholes and the partitions D D' rest upon a horizontal bottom shelf E, which is located a considerable distance above the top of the lower section, which provides a compartment beneath the bottom shelf E, as shown.

I claim—

The design for a desk-cabinet, as herein shown and described.

In testimony whereof I affix my signature in the presence of two witnesses.

FRANK S. THOMAS.
